TELEPHONE SWITCHBOARD

Edward A. Praisner, Montclair, N.J., assignor to Bell Telephone Laboratories, Incorporated, New York, N.Y., a corporation of New York

Filed Feb. 3, 1964, Ser. No. 78,502

Term of patent 14 years

(Cl. D26—14)

FIG. 1

FIG. 2

FIG. 3

FIG. 1 is a perspective front and top view of a telephone switchboard, showing my new design; and

FIG. 2 is a three-quarters side perspective view thereof; and

FIG. 3 is a side elevation thereof.

The broken line showing of legible matter in the drawing is for illustrative purposes only. Portions of the drawing figures are diagonally lined to indicate transparency.

The dominant features of my new design are shown in solid lines in the drawing. The back, not shown, is unornamented.

I claim:

The ornamental design for a telephone switchboard, substantially as shown and described.
